UNITED STATES PATENT OFFICE.

CHARLES ALDEN BONFILS AND HORACE G. BRADT, OF DENVER, COLORADO.

METHOD OF PRODUCING A COMBINED LINE AND HALF-TONE PRINTING PLATE.

No. 842,297.

Specification of Letters Patent.

Patented Jan. 29, 1907.

Application filed November 28, 1906. Serial No. 345,521.

To all whom it may concern:

Be it known that we, CHARLES ALDEN BONFILS and HORACE G. BRADT, citizens of the United States of America, residing at Denver, in the county of Denver and State of Colorado, have invented certain new and useful Improvements in Methods of Producing Combined Line and Half-Tone Printing Plates, of which the following is a specification.

The invention relates to an improved process of producing combined line and half-tone printing plates, and has for its object to obviate by the use of a simple mechanical process the laborious and skill-requiring method of lifting, cutting, and replacing the films on the negatives now commonly employed to obtain the desired effect.

The various steps employed in practicing our method are illustrated in the accompanying drawings, in the various views of which like parts are similarly designated, and in which—

Figure 1 represents the photograph or wash-drawing to be reproduced by the half-tone process; Fig. 2, the line-drawing to be reproduced in combination with the photograph or tint-drawing shown in Fig. 1; Fig. 3, the two representations in combination ready for reproduction; Fig. 4, a negative photographic plate of the combination shown in Fig. 3, the linework being "painted out;" Fig. 5, a negative photographic plate of the line-drawing; Fig. 6, a reproduction of the latter upon the metal printing-plate; Fig. 7, the completed printing-plate, and Fig. 8 an impression taken therefrom.

Referring to the drawings, 5 designates a picture, such as a photograph or wash-drawing, adapted to be reproduced by the half-tone process, and 6 a line-drawing executed for the purpose of zincographic reproduction and provided with diagonally-disposed registering marks 7.

The first step in our process consists in cutting out those portions of the drawing 6 where on the finished plate the half-tone work is to appear, after which the skeleton mask thus obtained is placed in the desired position over the picture shown in Fig. 1, as illustrated in Fig. 3. The combined representations are now reversely reproduced upon a photographic plate by means of a camera equipped with a prismatic lens. The negative thus obtained is by interposition between the original and the lens of a screen,

such as commonly used in half-tone work, adapted for photo-engraving, or, with other words, the solid tints of the original are represented on the plate by a multitude of juxtaposed dots or lines. In connection with this part of our invention it should be observed that in lieu of using a prismatic camera the negative may be made by means of an ordinary lens and the film subsequently lifted off and reversely replaced upon the glass plate.

The next step of our process consists in "painting out" the reproduction of the line-drawing on the negative by covering the extent of the skeleton mask (with the exception of the registering marks) with india-ink or other suitable opaque substance, as illustrated in Fig. 4. A second negative is now made of the line-drawing to a scale identical with that of the image on the first plate by photographing the skeleton mask placed upon a white background to obtain the effect of the original drawing or by the simpler method of removing the screen from the frame in which the two representations are held and interposing a sheet of white paper between the latter. As the last-named operation may be performed without disturbing the position of the frame in relation to the camera, it is obviously preferable to the first-named method. The image on the last-made negative, which like the one on the first plate is reversely produced thereon, is now reproduced upon a zinc or copper plate previously coated with bichromate of ammonia or other sensitive substance by the ordinary method of placing the one upon the other in a printing-frame and exposing the latter to the action of light. The sensitized surface of the metal plate (illustrated in Fig. 6) is now developed in the usual manner and preferably coated with photo-engraver's ink to render the impression, and more especially the registering marks, discernible, after which the plate is resensitized and replaced in the printing-frame beneath the painted-out negative, (shown in Fig. 4,) care being taken that the marks 7 on the negative and the plate are in perfect register.

When exposed to the action of the light, the sensitive substance applied over the line image being covered by the opaque substance on the negative is not acted upon by the light and in consequence washes off when the plate is subsequently developed, while the other portions of the negative bearing the half-tone work are reproduced upon the

plate, with the result that when after exposure the plate is developed it contains, as illustrated in Fig. 7, the combined impressions of the photograph illustrated in Fig. 1 and the delineation shown in Fig. 2 and will, after having been etched in the usual manner, produce, by means of the ordinary printing-press, prints such as illustrated in Fig. 8.

Instead of resensitizing the metal plate 10 after the line-work has been printed thereon the two prints may be made successively on the first coating, in which case the faintly-perceptible registering marks on the plate are accentuated by means of india-ink before 15 the half-tone negative is clamped in the frame.

To those skilled in the art to which our invention pertains its many advantages will be apparent as the method of coating the 20 negative with rubber and colodion and removing, cutting, and replacing its film as heretofore employed has at all times been associated with such difficulties as shrinking, shriveling, turning under, and lapping of the 25 films, the forming of air-bubbles between the film and the glass, &c., and can only be practiced by highly-skilled persons.

It will be understood from the foregoing that our process is adapted for the production 30 of printing-plates having either an enameled or an albumen surface.

Having thus described our invention, what we claim is—

1. The method of producing combined line 35 and half-tone printing plates, consisting in making a negative bearing the reversed image of a photograph or tint-drawing and the reversed outline reproduction of a line-drawing

covering the image of the line-drawing on the said negative with an opaque substance, producing a second negative bearing a reversed image of the line-drawing, successively producing prints of the two negatives upon a sensitized metal plate, and etching the latter.

2. The method of producing combined line 45 and half-tone printing plates consisting in skeletonizing a line-drawing, making a reversed negative of the latter and the original photograph or tint-drawing, covering the image of the said skeleton upon the negative 50 with opaque substance, producing a second, reversed negative of the line-drawing, successively producing prints of the two negatives upon the sensitized surface of a metal plate, and etching the latter.

3. The method of producing combined line and half-tone printing plates consisting in skeletonizing a line-drawing, making a reversed negative of the latter and the original photograph or tint-drawing, covering the image of the said skeleton upon the negative 60 with opaque substance, producing a second, reversed negative of the line-drawing, producing a print of the last-named negative upon the sensitized surface of a metal plate, 65 developing and resensitizing the latter, producing a print thereon from the first negative, and etching the plate.

In testimony whereof we have affixed our signatures in presence of two witnesses.

CHARLES ALDEN BONFILS.
HORACE G. BRADT.
